UNITED STATES PATENT OFFICE.

WILLIAM J. COULTER, OF CHESLEY, CANADA.

CLOTHES-DRIER.

SPECIFICATION forming part of Letters Patent No. 740,243, dated September 29, 1903.

Application filed March 27, 1903. Serial No. 149,823. (No model.)

To all whom it may concern:

Be it known that I, WILLIAM J. COULTER, a subject of the King of Great Britain, residing at Chesley, Province of Ontario, Canada, have 5 invented certain new and useful Improvements in Clothes-Drying Reels; and I do hereby declare the following to be a full, clear, and exact description of the invention, such as will enable others skilled in the art to which 10 it appertains to make and use the same.

My invention relates to clothes-drying reels; and it consists of a novelly-constructed lifting-post and lever connections whereby the lifting-post is raised and lowered.

15 The invention further consists of the general arrangement and combination of the several parts, as will be hereinafter fully described, and stated in the claim.

The principal object of the invention is to 20 improve this class of clothes-driers by simplifying the construction and cheapening the cost thereof without impairing their strength and durability and efficiency in operation.

Other objects of the invention will become 25 apparent upon a more detailed description thereof.

In the accompanying drawings, Figure 1 is a front elevation of my improved device, showing the arms in extended position; and Fig. 30 2, a side elevation of the lower portion of the device, the top being broken away.

In both views the letter *a* indicates the ground-post, which may be of any approved or desired construction, provided with eye-bands *a'* *a''*, arranged a suitable distance apart, which serve as guides in which a tubular post *b* is arranged to slide vertically. The upper end of said tubular post extends some distance above the upper end of the 35 ground-post and is provided with collars *b'* and *b''*. Pivoted to the lower collar are reel-arms *c*, which are adapted to be held in horizontally-extended position by braces *c'*, said

braces having one end pivoted to the arms and the other end suitably notched to engage a pin *c'*, projecting from the upper collar.

Fulcrumed on a pin *d*, projecting from the ground-post, is an operating-lever *d'*, and pivotally connected to one end of said lever is one end of a connecting-link *d''*, the other 50 end of said connecting-link being pivotally connected to one end of a hook *d''*, the other end of said hook entering the lower end of the tubular post. Secured to the ground-post is a stop-block *f*, which supports the 55 tubular post when in normal or lowered position. The tubular post is provided with an ornamental plug *g*. The lever connections are so arranged and connected that the tubular post carrying the reel-arms can be readily 60 and easily raised and lowered and is maintained in its raised position by slipping the operating-lever over against a pin *h*. When the device is not in use, the reel-arms and braces are folded closely against the tubular 65 and ground posts in compact form, and in transportation takes up but little room.

Having thus fully described my invention, what I claim, and desire to secure by Letters Patent, is—

The combination with a suitable ground-post provided with guides, of a tubular post vertically slideable in said guides, and carrying a clothes-reel, and lever connections for raising and lowering the tubular post, said 75 connections comprising a fulcrumed operating-lever, a hook engaging the lower end of the tubular post, and a link connecting the operating-lever and hook together.

In testimony whereof I affix my signature 80 in the presence of two witnesses.

WILLIAM J. COULTER.
